DESIGN FOR A CASING FOR A STRIP CUTTING MACHINE

Victor J. Sigoda, Great Neck, N. Y., assignor to
Man-Sew Corporation, New York, N. Y., a corporation of New York

Application March 13, 1948, Serial No. 145,078

Term of patent 14 years

(Cl. D55—1)

To all whom it may concern:

Be it known that I, Victor J. Sigoda, a citizen of the United States and a resident of Great Neck, county of Nassau, State of New York, have invented a new, original, and ornamental Design for a Casing for a Strip Cutting Machine, of which the following is a specification, reference being had to the accompanying drawing, forming part thereof.

In the drawing:

Fig. 1 is a perspective view of the casing for a strip cutting machine embodying my new design as viewed from the front and to the right; and

Fig. 2 is a perspective view as viewed from the front and to the left thereof.

I claim:

The ornamental design for a casing for a strip cutting machine, substantially as shown.

VICTOR J. SIGODA.
